ALICE RUBY BENZ AND FRANK M. ASHLEY, OF BROOKLYN, NEW YORK.

SHIRT FOR MEN'S WEAR.

Application filed September 25, 1924. Serial No. 739,829.

This invention relates to shirts for men's wear.

The object of this invention is to provide means for preventing the stiff collars worn with shirts having soft front portions against which the corners of the collars rest in wearing relation, from wearing holes in the shirt front.

A further object is to provide a shirt that will afford more protection to the wearer.

A further object is to provide a shirt having a pocket formed on the inner side thereof, the upper portion thereof serving as a lining to prevent undue wear at the points where the ends of the collar rest against the shirt front.

Referring to the drawings which form a part of the specification:

Fig. 1 is a view of the front portion of a shirt embodying the invention.

Fig. 2 is a view showing a portion of the back removed to disclose the lining portions sewed to the front portions.

Fig. 3 illustrates a modified form of construction in which the lining portion is abbreviated.

Fig. 4 is a vertical cross section taken on line X—X of Figure 1.

Fig. 5 is a vertical cross section taken on line Z—Z of Figure 2.

A indicates the front portion of a soft shirt made of thin striped material, a portion of which is broken away at A' to disclose a lining portion B, also of striped material, the stripes being indicated by C, being placed in superimposed relation and of the same pattern so that the appearance of the shirt will not be changed by reason of the lining when the material is thin and of loose or open weave.

The materials of the shirt and lining portion should be such that when the shirt shrinks due to washing, the shrinkage will be the same to prevent distortion of the garment.

The lining material is secured to the shirt

by sewing to the under side of the shoulder seam as indicated at D—D in Figure 1, and under the collar band E' and extending downward under the pleat F as indicated in dotted lines, and may be secured to the shirt front or left free as may be found most desirable.

When left free the lower edge may be hemstitched or otherwise secured against raveling.

G indicates a pocket formed between the lining and shirt front, the openings thereto being indicated at G'. The said pocket is formed by stitching a section of the material thereof along one side edge to the neckband seam and shoulder seam, and along two side edges to the inner face of the bosom, leaving one side edge adjacent the front opening of the shirt free to form a pocket opening.

It will be observed that the lining in all cases extends across the space where the lower ends or points of the collar rest against the shirt and this permits a relative movement of the shirt front and lining portion when the collar presses against the shirt front, the lining serving as a pad and preventing excessive wear on the portions against which the collar rubs.

Having thus described our invention we claim as new and desire to secure by Letters Patent as defined by the following claim:

A shirt having a bosom of soft material open at its front and having a front pleat, a neckband seam and a shoulder seam, a pocket of flexible material stitched along its top to the shirt by the shoulder seam and the neckband seam, said pocket being a substantially rectangular, elongated body open at its inner side and stitched at its upper and lower portions to the front pleat.

Signed at New York, in the county of New York and State of New York, September, A. D. 1924.
